UNITED STATES PATENT OFFICE.

LUDWIG HIRT, OF GREVENBROICH, GERMANY, ASSIGNOR TO THE MASCHIN-
ENFABRIK GREVENBROICH, OF SAME PLACE.

APPARATUS FOR DRYING SUGAR.

SPECIFICATION forming part of Letters Patent No. 655,710, dated August 14, 1900.

Application filed December 20, 1899. Serial No. 740,960. (No model.)

To all whom it may concern:

Be it known that I, LUDWIG HIRT, a subject of the King of Prussia, Emperor of Germany, and a resident of Grevenbroich, Kingdom of Prussia, German Empire, have invented certain new and useful Improvements in Apparatus for Drying Sugar, of which the following is a specification.

My invention refers to improvements in apparatus in which moist sugar in plates, bars, or any suitable shape is carried in baskets or other receptacles through a chamber by means of endless traveling chains, in which chamber the sugar is exposed to heat for drying purposes. In apparatus of this character heretofore employed the baskets or other receptacles were movably connected to the endless chains, but not detachable. Therefore the emptying of dried sugar from the baskets and the filling of the baskets with the moist sugar had to take place within the apparatus. These operations required considerable hand labor and it was necessary to maintain the apparatus at a standstill for a prolonged period, and the handling of the sugar plates caused an increase in breakage.

Now my invention has for its object to obviate the emptying of the dried sugar out of the baskets and the filling of the moist sugar into the baskets within the drying apparatus. For this purpose I arrange the mechanical power driving-gear of the drying apparatus to automatically stop the endless chains when the basket has arrived at the removal and filling end of the apparatus and to retreat said chains for a short distance. I likewise provide the discharge end of the apparatus with means for automatically depositing the baskets with dried sugar upon a small carriage, which in turn presents the filled baskets to the traveling chain to be automatically engaged thereby. Thus the filling of the baskets is suitably performed where the sugar plates are produced, while the emptying of said baskets takes place at a desirable point, where said sugar has to undergo further treatment, and in order to make my improvements fully clear I refer to the annexed drawings, in which—

Figure 1 shows the side view of the feed- 50
ing end of the apparatus, at which the withdrawal and insertion of the baskets take place. In this view the one wall of the drying-chamber is taken away to more clearly illustrate the working parts. Fig. 2 shows the gearing of 55

the chains in detached view. At the end of the drying-chamber *b* two chain-wheels *g* are mounted on one axle in proper bearings. At the other end of the chamber similar chain-wheels are mounted, 60 (which are not shown,) the said wheels at the two ends of the chamber carrying two endless chains *c*, provided with rollers *e* and cross-bars *d* between each pair of rollers *e*. The baskets *a*, provided with suitable hooks, are 65 adapted to be suspended on said cross-bars *d*, and are thereby traveling with the chains through the chamber, which is heated by suitable devices. The lower rails *f*, upon which the chain-rollers travel, are extended at the 70 front end of the apparatus at *h* to receive a carriage *i*, capable of being pushed into the chamber *b* with a basket *a* filled with moist sugar and of being withdrawn out of the apparatus with a basket containing the dried sugar after 75 the travel through the chamber. On one end of one of the shafts of the chain-wheels *g* and outside the chamber *b* a driving or worm wheel *p* is keyed. Said wheel has teeth for the endless screw or worm *q* to take into them. 80 Said worm is mounted on shaft *t*, carrying two loose pulleys *u* and one fixed pulley *v* between them. Belts *u' u²* run on said two loose pulleys from any convenient pulley *u³* and counter-shaft in the usual and well-known 85 manner, the one belt *u³* being open and the other *u'* crossed in order to make the rotation of the screw-shaft reversible. The belts are, as usual, running within proper forks *o n*, mounted on a shifting bar *k* to reverse the 90 traveling direction of the endless chains. This shifting bar *k* is connected by means of lever *x*, pivoted at *z* to the shifting bar *k**, which is provided with a handle. The shifting bar *k** is provided with a nose *l*. The lever *x* 95 may be dispensed with, and the bar *k*, which is provided with the forks, may be prolonged and provided with nose *l*. The driving-wheel

p is provided with a series of holes or apertures *s* near its periphery for receiving a removable bolt *r*, which in the instance shown in Fig. 2 is inserted into one of the holes at 5 *w* and projects to the opposite side of said wheel. If now during the rotation of the driving or worm wheel *p* the bolt strikes against said nose *l*, the bar *k* is shifted, thereby causing the belt *u*² (the driving-belt) to 10 run from the fixed pulley *v* upon one of the loose pulleys *u*. This movement, however, is so limited that the driving-belt runs upon a loose pulley; but the second or cross belt *u'*, which causes the retreating motion, will 15 not have been moved to the fixed pulley *v*. Thus the chain-wheels and endless chains with the baskets are brought to a standstill.

The position of the bolt in the wheel is such that the bringing of the machine to a standstill will occur when a basket with dried sugar has arrived within the opening at the 20 front end of the chamber and is in such position that the carriage *i* is free to be pushed underneath said basket.

25 If a further shifting of the belt-bar *k*, with its forks, is now effected by hand, the second or reversing belt *u'* will be shifted onto the fixed pulley, so that the rotation of shaft *t* is reversed, and thereby the direction of movement of the chains is reversed for a short distance or until the said basket is lowered and deposited upon the carriage *i* and its hooks are disengaged from their cross-bar *d* between the chains. Thus the basket may be 30 withdrawn and deposited on the carriage by the operator. The operator now places a new basket with moist sugar or the same basket refilled with moist sugar on the carriage *i* and pushes the latter into the apparatus into such a position that if the chains continue their regular forward travel the basket will be caught at its hooks by a cross-bar and be carried along into the chamber. To accomplish this last-mentioned movement, 35 the operator withdraws the bolt *r* and inserts it into the next aperture *s* of the driving-wheel. Thereby the bolt *r* is out of the path of the nose *l* during the next movement of the wheel. The operator may now seize the 40 handle and push the bar in an opposite direction, thereby shifting the belts so that the one *u*², which causes regular travel, runs upon the fixed belt-pulley. The bolt inserted in the next eye will by the continuation of 45 rotation of its wheel come into contact with the nose *l*, thereby again shifting the belts in the manner hereinbefore described to bring the machine to a momentary standstill. The same mode of working may then be repeated 50 indefinitely.

If the width of the drying apparatus has a convenient extent, two or more baskets may be suspended upon one cross-bar *d*.

Having now described my invention, I claim—

65

1. In an apparatus for drying sugar in baskets, the combination of traveling endless basket-conveying chains, a heating-chamber through which said chains travel, a driving-gear for said chains, said driving-gear comprising a worm-wheel secured to one of the chain-wheel shafts, a worm coöperating with said worm-wheel, a fixed and two loose belt-pulleys on the shaft of said worm, means for shifting the belt on said pulleys to bring the 70 chains to a standstill or to cause a forward or a reverse movement of the endless chains and means for automatically effecting a movement of said shifting means.

75

2. In an apparatus for drying sugar in baskets, a gear consisting of a worm-wheel on one of the chain-wheel shafts, a screw taking into said worm-wheel, said worm-wheel having apertures near the periphery thereof, a removable bolt adapted to be inserted in any 80 of said apertures and a bar for shifting the belts, a nose protruding from said bar, said nose lying within the path of rotation of the bolt of said worm-wheel.

85

3. In an apparatus for drying sugar in baskets, the combination of a drying-chamber, endless chains moving in said chamber, rollers carried by said chains, rails for carrying said rollers and extending at one end of the apparatus out of the drying-chamber, a carriage traveling on said extensions of the rails and baskets provided with hooked hangers, which baskets are removable from and adapted to be carried by said carriage into and out of said heated chamber and to be automatically 90 caught and released from said endless chains at a single point in the apparatus, whereby the baskets may be removed from or deposited on said carriage and means for causing a forward or reverse movement of the chains at 95 will or for maintaining the chains against movement.

95

4. In an apparatus for drying sugar in baskets, a carriage for transporting the baskets into the reach or out of the reach of the endless chains traveling through the heated chamber, a reversing belt-gear for moving the endless chains in the forward or reverse direction and means for partly automatically shifting the belts in one direction and for shifting the belts by hand in the opposite direction.

100

In testimony that I claim the foregoing as my invention I have signed my name, in presence of two witnesses, this 7th day of December, 1899.
